CLAIM

The ornamental design for an automated teller machine cassette lock, as shown and described.

DESCRIPTION

FIG. 1 is a top, front, and left side perspective view of an automated teller machine cassette lock showing my new design, the broken-line disclosure being understood to form no part of the claimed design;

FIG. 2 is a top, rear, and right side perspective view thereof;

FIG. 3 is a top plan view thereof;

FIG. 4 is a bottom plan view thereof;

FIG. 5 is a front elevational view thereof;

FIG. 6 is a right side elevational view thereof;

FIG. 7 is a rear elevational view thereof; and,

FIG. 8 is a left side elevational view thereof.
